UNITED STATES PATENT OFFICE.

CHARLES GULDEN, OF NEW YORK, N. Y.

DESIGN FOR A BOTTLE.

SPECIFICATION forming part of Design No. 23,892, dated December 25, 1894.

Application filed November 22, 1894. Serial No. 529,655. Term of patent 7 years.

To all whom it may concern:

Be it known that I, CHARLES GULDEN, a citizen of the United States, and a resident of the city, county, and State of New York, have 5 invented and produced a new and original Design for Bottles, of which the following is a full, clear, and exact description.

The leading feature of my design consists in a bottle of essentially the configuration and 10 representation shown in the accompanying drawings, in which--

Figure 1 is a side view of a bottle embodying my design; and Fig. 2 is a horizontal section thereof on line 2—2 of Fig. 1.

15 In the drawings, A is the body of the bottle, which is substantially cylindrical in cross-section. The lower portion of this body slopes

in a gradual curve, B, toward the base or bottom C of the bottle.

The bottle is provided with a neck D, which 20 extends from the body portion and is contracted at or about its middle portion, and which forms a breast or shoulder E where it joins the body portion of the bottle. The upper portion of the neck terminates in a 25 flaring mouth or lip F.

What I claim is--

The design for a bottle substantially as shown and described.

CHARLES GULDEN.
